UNITED STATES PATENT OFFICE.

JOSEPH ZALOWITZ, OF NEW YORK, N. Y.

GEM SETTING.

1,421,339.

Specification of Letters Patent. Patented June 27, 1922.

Application filed August 10, 1921. Serial No. 491,172.

To all whom it may concern:

Be it known that I, JOSEPH ZALOWITZ, a citizen of the United States, resident of New York, in the county of New York and State 5 of New York, have made a certain new and useful Invention in Gem Settings; and I declare the following to be a full, clear, and exact description of the same, such as will enable others skilled in the art to which it 10 appertains to make and use the invention, reference being had to the accompanying drawings, and to letters or figures of reference marked thereon, which form a part of this specification.

15 Figure 1 is a plan view of the invention.

Figure 2 is a section on the line 2—2 Figure 1.

Figure 3 is a side view of the invention.

20 Figure 4 is a section on the line 4—4 Figure 1.

The invention has relation to gem settings, and particularly to cluster settings, having for an object to provide a more secure setting for the stones, particularly adapted for 25 closed back settings, rendering the setting of the stones more simple, and giving a better coloring to the stones as set.

The invention consists in the novel construction and combinations of parts, as hereinafter set forth.

In the accompanying drawings illustrating the invention, the numeral 2 designates the body of the setting, provided with an outer circumferential series of teeth 3, converging towards the back of the setting, into points 4, extending backwardly of said body, and adapted for attachment to an annulus 5, by a suitable cement or solder, a pin 6, being in some cases secured to said annulus.

Each tooth 3 is indented centrally thereof, at 7, thereby making each tooth of V-form in side or edge view, the adjacent branches of each pair of said teeth being 45 united to form a projection 8 in the nature of a point projection. Each pair of said teeth therefore forms a W in side view, as in Figure 3 of the drawings and is separated from adjacent pairs of similarly formed teeth 50 by spaces or indentations 9, which extend more deeply or inwardly of the setting than does the indentation 10 between the members of each pair of said teeth.

For each pair of teeth there is provided 55 a conical or tapered recess or seat 11, for a stone, and the projection 8 of each pair of

teeth is in line radially with the center of the related seat 11 and the center of the body of the setting. The annular series of recesses or seats 11, meet each other tangentially, triangular projections 12 being thereby formed and filling in the angles between said seats at the outer sides thereof, each said projection 12 being united with the adjacent branches of adjacent pairs of 65 teeth and the indentation 9 extending centrally inward of the triangular projection 12 to make said projection of V form, the branches of which are adapted to be spread by a punch placed thereon to overhang the 70 seat 11 and a stone 13 fitting in said seat, and thereby holding the stone in place, a punch placed upon the projection 8 spreading the same and causing it to also overhang the seat 11 and the stone for the same purpose. 75 It will be noted in this connection that the single projection 8 and the V-form projections 12 both project above the seat 11 so as to be adapted to be spread to overhang said seat.

80 A central seat 14 of conical form is tangential to the annular series of seats 11, thereby providing projections 15 filling in the intervals between the seats and capable of being spread by a punch placed thereon to 85 overhang said central seat and a stone 16 located therein to hold the stone in place, and also capable of being spread to hold the outer series of stones 13 in place, said projections 15 similarly all projecting above the 90 seat 14.

Each pair of teeth 3 formed as stated is made up of four inclined strut members 17, united centrally to form the projection 8, and united at the ends to the triangular 95 projections 12, thereby providing means for bracing the projections 8 and 12 when being spread for the purpose stated and avoiding the distortion of the setting in the operation of securing the stones in place therein. 100

In spreading the projections 15 for the purpose stated, said projections will be braced against the action of the punch by the substantially pyramidal portions 18 of the body of the setting lying immediately 105 under the said projections, and connected with each other annularly around the setting.

The annular series of seats 11 for the stones meet each other tangentially below 110 the face of the body of the setting, this being true as to the meeting of the center seat

14 with the seats 11, whereby the projections 8, 12 and 15 project vertically or parallel to the longitudinal central axis of said seats, being thereby adapted to be more readily 5 spread or upset to overhang the stones and secure the same in position.

I claim:—

1. In a gem setting for clusters, a body 10 having tapered seats in an annular series and a central tapered seat, the peripheries of said seats meeting each other to form projections located between the seats and adapted to be upset to secure the stones in 15 said seats in position, the outer of said projections being cut away to provide V-form 40 projections and point projections in line radially with the centers of said seats and the center of the setting.

2. In a gem setting for clusters, a body 20 having tapered seats, the perimeters of said seats meeting each other below the face of said body, projections thereby formed and adapted to be spread or upset over the edges 25 of stones in said seats to secure the same in position and strut braces for said projections in the spreading or upsetting thereof.

3. In a gem setting for clusters, a body 30 having tapered seats the perimeters of which meet each other tangentially below the face of said body, V-form projections located be-

tween said seats, and point projections in line radially with the centers of said seats and the center of the setting, said projections being adapted to be spread or upset to 35 secure the stones in position, and strut braces for said projections in the spreading thereof.

4. In a gem setting for clusters, a body 40 having tapered seats the perimeters of which meet each other tangentially below the face of said body, V-form projections located between said seats, and point projections between said V-form projections, all of said 45 projections being adapted to be spread to overhang stones in said seats, and strut braces backing up said projections and converging towards the back of the setting.

5. In a gem setting for clusters, a body 50 having tapered seats the perimeters of which meet each other below the face of said body, V-form projections located between said seats, and adapted to be spread to overhang said seats, and braces backing up said projections and retreating backwardly.

In testimony whereof I affix my signature in presence of two witnesses.

JOSEPH ZALOWITZ
